[57] CLAIM

The ornamental design for a housing for a single reel tape cartridge, as shown and described.

DESCRIPTION

FIG. 1 is an isometric view of a housing for a tape cartridge showing our new design;

FIG. 2 is a top view thereof;

FIG. 3 is a bottom view thereof;

FIG. 4 is a front view thereof;

FIG. 5 is a back view thereof;

FIG. 6 is a right side view thereof; and,

FIG. 7 is a left side view thereof.

The broken line showings are for illustrative purposes only and form no part of the claimed design.
